Attorney

UNITED STATES PATENT OFFICE.

WILLIAM A. SMITH, OF DENVER, COLORADO, ASSIGNOR TO THE DENVER ROCK DRILL MANUFACTURING CO., OF DENVER, COLORADO, A CORPORATION OF DELAWARE.

DOLLY MECHANISM FOR DRILL-SHARPENERS.

1,253,292.

Specification of Letters Patent. Patented Jan. 15, 1918.

Application filed March 19, 1917. Serial No. 155,831.

To all whom it may concern:

Be it known that I, WILLIAM A. SMITH, a citizen of the United States, residing at Denver, in the county of Denver and State 5 of Colorado, have invented certain new and useful Improvements in Dolly Mechanism for Drill-Sharpener, of which the following is a specification.

The present invention relates more particularly to the dolly mechanism of drill 10 sharpening apparatus.

One of the objects is to provide a dolly holder or support of practical, novel and simple character which will permit the ready 15 removal and replacement of the dolly.

As is well known to those skilled in this art, drill bits are now almost universally provided with a longitudinal bore therethrough for the purpose of directing cleansing fluid to the bottom of the drill hole, and as a consequence, in the sharpening operation means are necessary to keep the bore at the bit end of the drill in properly open condition. The practice therefore is to employ a projection on the dolly which enters 20 the bore. These projections being relatively small in cross section, soon become burned, worn and misshapen. An important object therefore is to provide a dolly with a removable pin for this purpose, the same being readily detachable, and means being employed, whereby it is properly held in operative position when in use.

An embodiment of the invention is illustrated in the accompanying drawings, 35 wherein:—

Figure 1 is a view partially in elevation and partially in section of a portion of a drill sharpening apparatus, illustrating the 40 improved dolly and dolly holding means.

Fig. 2 is a plan view of the dollying hammer with the associated parts.

Fig. 3 is a cross sectional view on the line 3—3 of Fig. 2.

Fig. 4 is a detail longitudinal view on an enlarged scale through the front portion of the dolly to illustrate more clearly the mounting of the dolly pin.

Similar reference numerals designate cor- 50 responding parts in all the figures of the drawings.

In the embodiment disclosed, the drill bit holding means are illustrated in Fig. 1, comprising a pair of coacting clamping jaws 5 and 6, which it is believed unnecessary to

disclose or describe in detail. Projecting from one side of the support 7 carrying these jaws is a horizontal arm 8, on which is mounted a dollying hammer 9. It will be understood that this hammer may be of 60 any well known character, including a cylinder member 10 within which reciprocates a hammer piston 11. The cylinder 10 is provided with a reduced front head portion 12.

Mounted on the said head portion 12 is a 65 dolly holder comprising longitudinal sections 13 and 14. The section 13 has at its rear end a collar portion 15 that surrounds and is suitably held upon the head 12, the section 14 abutting against the collar 15. 70 These two sections are held in assembled relation by transverse tie bolts 16 pivoted at their lower ends, as shown at 17 to ears 18 formed upon the lower section 13. The tie bolts pass through slots 19 formed in ears 20 75 that project from opposite sides of the upper section 14. Suitable nuts 21 are threaded upon the upper ends of the bolts and bear upon the upper sides of the ears 20, thereby effectively holding the two sections together. 80 At the same time, it will be evident that these sections are easily separated by loosening the nuts 21 until the bolts 16 can be swung outwardly or disengaged from the upper section, whereupon said upper section can be 85 detached from the lower section.

The dolly holder is provided with a longitudinal bore 22 formed partly in each section, and in this bore is slidably located a dolly, the same consisting of a shank 23 that 90 is located in the bore, and an integral head 24 disposed in advance of the holder. The rear end of the dolly has a depending lug 25 that is abutted against by a suitable return piston 26 mounted in the lower section 95 13. So far as thus described, the dolly and the return means is a known structure.

In the present embodiment, it will be noted that said dolly is provided with a longitudinal bore having a front portion 27 of 100 less diameter than the rear portion 28, thereby producing an internal shoulder 29. In said front portion 27 is detachably fitted a dolly pin 30 having a pointed front end 31 that projects from the head 24, and having 105 a rear head 32 that is fitted in the portion 28 of larger diameter, said head abutting against the shoulder 29. In rear of the head 32 and bearing against the same is a tappet pin 33 that is located in the portion 28 of 110

the bore and extends to the rear end of the dolly, being flush with the rear face thereof. With this structure, it will be evident that the dolly pin 30 is effectively held in place and that when the hammer piston 11 strikes the rear end of the dolly, it also strikes the tappet pin 33, and thus maintains the projecting end 31 in operative position. When the pin 30 becomes worn or useless from any cause, it is only necessary to separate the sections of the holder, which as already explained, can be easily accomplished, remove the dolly and hold it in upright position, whereupon the tappet pin 33 will drop out and the dolly pin 30 can be easily removed, a new pin can then be placed in position, and the tappet pin replaced.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In apparatus of the character set forth, the combination with a hammer including a barrel and a piston operating therein, of a dolly holder at one end of the hammer comprising separable sections, one of which is mounted on the barrel, means for securing the sections together, and a dolly mounted between the sections and removable when they are separated.
2. In apparatus of the character set forth, the combination with a hammer including a barrel and a piston operating therein, of a dolly holder at one end of the hammer comprising separable longitudinal sections, one of which is provided with a collar that surrounds the barrel, transverse means securing the sections together, and a dolly mounted between the sections and removable when they are separated.
3. In apparatus of the character set forth, the combination with a hammer including

a barrel having a piston operating therein, of a dolly holder at one end of the hammer comprising separable sections, one of which is mounted on the barrel, means for securing the sections together, a dolly mounted between the sections and removable when said sections are separated, and means for returning the dolly against the action of the hammer, said means being mounted on one of the sections.

4. In apparatus of the character set forth, the combination with a dolly support, of a dolly therein having a longitudinal bore, a removable dolly pin located in the bore and projecting from the front end of the dolly but terminating short of its rear end, and a tappet located in the bore in rear of the dolly pin.

5. In apparatus of the character set forth, the combination with a dolly support, of a dolly therein provided with a longitudinal bore having portions of different diameters, a removable dolly pin located in a portion of the bore of one diameter and projecting from the front end of the dolly but terminating short of its rear end, and a tappet located in the portion of the bore of different diameter and disposed in rear of the dolly pin.

6. In apparatus of the character set forth, the combination with a dolly support, of a dolly therein having a head and a shank and provided with a longitudinal bore, the front portion of said bore being of less diameter than the rear portion, forming an internal shoulder, a dolly pin having a shank located in the portion of less diameter and projecting beyond the front end of the dolly, said dolly pin also having a head located in the portion of the bore of larger diameter and associated with the internal shoulder, and a tappet pin disposed in the portion of the bore of larger diameter and having its front end arranged against the head of the dolly pin.

In testimony whereof, I affix my signature in the presence of two witnesses.

WILLIAM A. SMITH.
